CARVING FORK OR THE LIKE

Edward H. Rodier, Waltham, Mass.

Application January 3, 1955, Serial No. 33,816

Term of patent 14 years

(Cl. D44—29)

Figure 1 is a rear elevational view of a carving fork or the like showing my new design;

Figure 2 is a side elevation of the same;

Figure 3 is a front elevation of the same, and

Figure 4 is a view in end elevation looking in the direction of the rear end of the handle.

I claim:

The ornamental design for a carving fork or the like, as shown.
